UNITED STATES PATENT OFFICE.

AUGUST BISCHOFF, OF PHILADELPHIA, PENNSYLVANIA.

FASTENING FOR ARTIFICIAL TEETH.

SPECIFICATION forming part of Letters Patent No. 689,158, dated December 17, 1901.

Application filed March 26, 1901. Serial No. 52,908. (No model.)

To all whom it may concern:

Be it known that I, AUGUST BISCHOFF, a citizen of the United States, residing in the city and county of Philadelphia, State of Pennsylvania, have invented a new and useful Improvement in Fastenings for Artificial Teeth, of which the following is a specification.

My invention relates to an improvement in fastenings for artificial teeth, which consists in securing a notched or serrated plate to the said teeth.

It further consists of novel details of construction, all as will be hereinafter set forth.

Figure 1 represents a perspective view of a fastening embodying my invention, showing the same in position on the teeth. Fig. 2 represents a vertical sectional view in line xx , Fig. 1. Fig. 3 represents a horizontal sectional view on line yy , Fig. 1.

Similar letters of reference indicate corresponding parts in the figures.

Referring to the drawings, A designates a fastener for artificial teeth, the same consisting of a plate B, having openings therein, through which are adapted to pass the pins C, having the heads D thereon, said pins securing said plate to the teeth E. Projecting from the plate B are the ears F, forming a channel therebetween, the edges of said ears being provided with shoulders G and having the notches or cut-away portions H, it being seen that by reason of the channel, the shoul-

ders, and the notches the plate B and teeth can be securely fastened to vulcanite or rubber properly applied, it being seen that the material will enter the channel and the notches and engage the shoulders.

It will of course be evident that various changes may be made by those skilled in the art which will come within the scope of my invention, and I do not therefore desire to be limited in every instance to the exact construction herein shown and described.

Having thus described my invention, what I claim as new, and desire to secure by Letters Patent, is—

1. In a fastener for teeth, a plate secured thereto, ears projecting at an angle therefrom, and shoulders projecting at an angle from said ears.
2. In a fastener for teeth, a plate secured thereto, ears projecting at an angle therefrom, and shoulders projecting at an angle from said ears, the latter being notched.
3. In a fastener for teeth, a plate having its sides bent in opposite directions with a channel therebetween, the said sides being provided with angularly-disposed terminals and being notched.

AUGUST BISCHOFF.
